United States Patent Office.

ISAAC A. SHEPPARD, OF PHILADELPHIA, PENNSYLVANIA.

Design No. 2,673, dated June 11, 1867.

DESIGN FOR THE PLATES OF A STOVE.

The Schedule referred to in these Letters Patent and making part of the same.

TO ALL WHOM IT MAY CONCERN:

Be it known that I, ISAAC A. SHEPPARD, of Philadelphia, county of Philadelphia, State of Pennsylvania, have invented or produced a new and original Design for the Plates of the "Myrtle Heating-Stove;" and I do hereby declare that the accompanying drawing and the following explanation thereof form a full, clear, and exact description of the said design. In the accompanying drawing—

Figure 1 is an exterior elevation of the "Myrtle" heating-stove.

Figure 2, an exterior view of some of the plates; and

Figure 3, a plan view of the cap-plate.

A is the base, B the cylinder, and C the cap of the stove, which is supported by feet D, secured to the base. On each of the feet, at the edge of which is a plain beading, is an ornament representing a sprig. The lower base-plate is bordered by a plain beading. At the edge of the upper base-plate is a series of sprigs, and on the sides of the base are ornamental figures c, of the form shown in the drawing. The door frame E is bordered by a plain beading, and by the ornamental figures shown. On the edge of the door is a series of leaves, and in the centre of the door are scrolls with figures 1867. On the cap-plate are two annular beadings e f, the former enclosing a series of figures of the character shown in fig. 3, and between the two beadings is a wreath of leaves. At the edge of this plate is a series of sprigs.

I claim the design for the plates of the "Myrtle" heating-stove, substantially as shown in and by the accompanying drawing.

In testimony whereof I have signed my name to this specification in the presence of two subscribing witnesses.

ISAAC A. SHEPPARD.

Witnesses:

CHARLES E. FOSTER,
W. J. R. DELANY.
